STOCKING

Paul R. Nestler, Walnut St., Green Lane, Pa.

Filed Apr. 26, 1965, Ser. No. 84,968

Term of patent 14 years

(Cl. D47—7)

FIG. 1 is a schematic view of a stocking, showing my new design; and

FIG. 2 is a scale size fragmentary plan view of the fabric forming the body thereof, the welt, heel, and toe portions being conventional.

I claim:

The ornamental design for a stocking, as shown and described.
